CLAIM

The ornamental design for a firepit, as shown and described.

DESCRIPTION

FIG. 1 is an upper perspective view of the firepit of the present invention showing my new design;

FIG. 2 is a top plan view thereof;

FIG. 3 is a front elevational view thereof;

FIG. 4 is a first side elevational view thereof;

FIG. 5 is a second side elevational view thereof;

FIG. 6 is a rear elevational view thereof; and,

FIG. 7 is a bottom plan view thereof.

The broken lines in the drawings illustrate portions of the firepit that form no part of the claimed design.
